UNITED STATES PATENT OFFICE.

JOHN S. NORTH, OF PHILADELPHIA, PENNSYLVANIA, ASSIGNOR TO NORTH BROS' M'F'G CO., OF PHILADELPHIA, PENNSYLVANIA, A CORPORATION OF PENNSYLVANIA.

DISPLAY BOX.

Application filed April 29, 1924. Serial No. 709,860.

The object of my invention is to provide a box in which goods are packed, particularly mechanical tools, and to provide means whereby a tool can be displayed on the box.

10 A further object of the invention is to provide a display box of this type with a slotted bottom, which is normally closed, and, which, when the box is inverted, can be used to receive and hold a tool, such as a 10 drill having a wheel that extends into the slot.

In the accompanying drawings,

Fig. 1 is an inverted perspective view of my improved display box;

15 Fig. 2 is a view of the box tilted and showing a drill mounted thereon;

Fig. 3 is a transverse sectional view of the box;

20 Fig. 4 is a detached sectional perspective view of the bottom of the box showing the bottom partially cut to form a slot; and,

Fig. 5 is a perspective view similar to Fig. 4 showing the slot open.

The body of the box 1 has a bottom 2 with 25 a partially formed slot therein outlined by longitudinal cut and transverse cuts 3, said transverse cuts being at each end of the longitudinal cut. The portion 4 forms a closure for the slot, when in the position shown 20 in Figs. 1 and 4, when the box is packed for shipment.

The cover 5 of the box has a deep flange 6, in the present instance, which encloses the body 1, as clearly shown in Fig. 3. When it 25 is desired to display the tool, which, in the present instance, is a drill *a* having a beveled gear wheel *b*, and which has been packed in the box, the body 1 of the box is

tilted, as shown in Fig. 2, and rests upon one of the end flanges 6 of the lid 5. The closure 4 is then separated from the body of the box on the lines 3, and is turned in, as clearly shown in Fig. 5, so as to open the slot 7 through which the wheel *b* of the drill extends. This allows the drill to lie 45 flat upon the inverted bottom of the box and the handle *c* can be arranged to lie parallel with the bottom, as clearly shown in Fig. 2, making a very attractive display, and at the same time, the drill is held rigidly 50 in position on the box. When it is desired to pack the drill in the box, the drill is removed and the closure 4 is pressed down into position, as illustrated in Fig. 4 closing the slot 7 in the bottom of the box, after 55 which the tool can be packed therein in the ordinary manner. By making the slot in the bottom of the box, the top is left free for labels.

I claim:

1. A display box having a body portion provided with a bottom; a slot at one end of the bottom for the passage of a portion of a tool to be displayed; and a closure pivoted to one side of the slot and arranged 65 to close the slot when a tool is packed in the box.

2. The combination in a box of a body portion having a bottom, said bottom having a partial cut outlining a slot and a closure for the slot so that, when it is desired to display a tool on the inverted body of the box, the closure can be forced in to open the slot for the reception of a portion of the tool; and a flanged cover for the box.

JOHN S. NORTH.
